UNITED STATES PATENT OFFICE.

GABRIEL RASGORSHEK AND JOHN RASGORSHEK, OF PLATTS MOUTH,
NEBRASKA.

STOVE-PIPE CLEANER.

SPECIFICATION forming part of Letters Patent No. 284,897, dated September 11, 1883.

Application filed March 21, 1883. (Model.)

To all whom it may concern:

Be it known that we, GABRIEL RASGORSHEK and JOHN RASGORSHEK, of Plattsmouth, in the county of Cass, and in the State of Nebraska, have invented certain new and useful Improvements in Stove-Pipe Cleaners; and we do hereby declare that the following is a full, clear, and exact description thereof, reference being had to the accompanying drawings, making a part of this specification, in which—

Figure 1 is a perspective view of our improved device arranged for introduction into a pipe or flue. Fig. 2 is a like view of the same when expanded to its full size. Fig. 3 is a vertical central section of a stove-pipe, showing said device in use within the same; and Fig. 4 is a like view of a section of pipe and of a chimney, showing said device in use 20 within the latter.

Letters of like name and kind refer to like parts in each of the figures.

The design of our invention is to enable chimney-flues and stove-pipes to be readily 25 and thoroughly cleaned from soot and ashes; and to this end it consists in the arrangement, construction, and combination of parts, as hereinafter described, and specifically pointed out in the claims.

In the annexed drawings, A represents a metal rod, which at one end is provided with a handle, a, and to its opposite end has attached a number of wires, a', that from thence extend in a curve forward and outward, and 35 at their outer ends are connected with a circular disk of flexible material, B. Said wires are preferably constructed in pairs with the outer ends of each pair connected together, and are arranged at and attached to equidistant points around the edge of said disk. The wires a' have such outward spring of their front ends as to cause the disk B to be drawn taut; but by means of a ring, C, which is 40 adapted to slide over said wires, the outer ends of the latter may be drawn together, as shown in Fig. 1, and such part of the device made to occupy but slightly more transverse space than other portions of the same. A

cross-bar, c, extending from side to side of the ring C between the wires a', insures the lateral 50 position of said ring, while a hook, D, that is pivoted upon the outer end of one of said wires, is adapted to engage with and lock in place said ring when the latter is moved to the outer limit of its motion and confines the outer ends 55 of said wires. The hook D has an arm, d, which extends forward and slightly outward and furnishes a means whereby when desired said hook is released from engagement with the ring C, and the wires a' permitted to operate to expand the disk B, as is hereinafter described.

In use the cleaner described is arranged as shown in Fig. 1, and its front end passed carefully into a stove-pipe, E, or chimney-flue F, after which, by means of a slight turn of the device, the arm d is brought into contact with some portion of said pipe or chimney, and the hook D tripped, so as to release the ring C and 65 permit of the expansion of the disk B. The 70 cleaner, being now ready for use, is moved longitudinally through the pipe or flue, and as the edge of said disk is pressed against the inner surface of the same, soot or ashes adhering thereto will be detached and moved with the 75 device.

For convenience in the use of the cleaner, sliding or hinged doors e are provided within the pipe E, such doors being placed at suitable points within the vertical or horizontal 80 portions or at the outer bend of the elbow, and when opened permitting said cleaner to be inserted and operated, as shown in Figs. 3 and 4.

Having thus fully set forth the nature and 85 merits of our invention, what we claim as new is—

1. The hereinbefore described pipe and chimney cleaner, consisting of the rod A, provided with the wires a', and the disk B, secured to and made expandable by means of said wires, substantially as and for the purpose specified.

2. In combination with the outwardly-curving wires a', having attached thereto the disk B, the ring C, adapted to slide over and to

close together said wires, substantially as and for the purpose shown.

3. In combination with the ring C and the wires a' , the hook D, provided with the arm d , and arranged to engage with and to confine in place said ring, substantially as and for the purpose set forth.

In testimony that we claim the foregoing we

have hereunto set our hands this 5th day of March, 1883.

GABRIEL RASGORSHEK.
JOHN RASGORSHEK.
